CLAIM

The ornamental design for a shaving razor cartridge, as shown and described.

DESCRIPTION

FIG. 1 is a perspective view of a shaving razor cartridge showing our new design;

FIG. 2 is a top view thereof;

FIG. 3 is a bottom view thereof;

FIG. 4 is a left view thereof;

FIG. 5 is a right view thereof; and,

FIG. 6 is a front view thereof.

The broken lines illustrate portions of the shaving razor cartridge and form no part of the claimed design.
